CHECK BOOK

Filed June 2, 1926

UNITED STATES PATENT OFFICE.

SAMUEL J. HALPERIN, OF BROOKLYN, NEW YORK.

CHECK BOOK.

Application filed June 2, 1926. Serial No. 113,323.

My invention relates to check books of the character in which the check entry leaves are separate from the checks. Heretofore, entry leaves of check books have 5 been distributed in sets of one or more among the checks. But in this form of check book, as well as in the more common form in which each check and entry stub form one leaf, when the checks are torn out, 10 the binding stubs of both the checks and the entry leaves make the check book thick at the binding end and thin at the free end of the covers. Further, the entry leaves when distributed among the checks, are so scattered 15 as to make it inconvenient and difficult to make the entries and to keep track of the balance.

My invention consists primarily in binding all the entry leaves together, preferably 20 in front of all the checks, and secondly in providing means for conveniently and cleanly removing all the binding stubs of the checks from the covers when the checks are used up, so that the book of entry leaves 25 then remaining will be equally thin at both ends for more convenient storage, substantially as hereinafter described and claimed.

In order that my invention may be clearly understood, I shall first describe in detail 30 the mode in which I at present prefer to carry the invention into effect and then particularly point out the invention in the claims.

Reference is to be had to the accompanying 35 drawings forming part of this application, in which like parts are designated by the same numerals in all the figures.

Figure 1 is a perspective view of a check book embodying my invention, parts being 40 broken away.

Figure 2 is a longitudinal sectional view of the same.

Figure 3 is a longitudinal sectional view 45 showing the checks and their binding stubs detached from the book.

In making the check book illustrated, I assemble all the entry leaves 4 together at one end, preferably the front of the book, and all the checks 5 together at, in this instance, the back of the book, and bind the 50 assembled entry leaves 4 and checks 5 between the front and back covers 6 and 7 respectively, so that all the check entries will be together and entering and balancing thus greatly facilitated.

Each entry leaf is printed by preference

with a vertical column 8 of check numbers, a vertical column 9 for the respective dates, a column 10 for the names of the respective drawees, a column 11 for the check purposes 60 and columns 12 and 13 for the check amounts and totals respectively.

I prefer to bind the assemblage of entry leaves 4 between the front cover 6 and a heavy blank leaf 14 in two short plies of 65 strong binding paper or fabric 15, one of the plies being pasted on the inside of the front cover and the other on the blank leaf 14.

In like manner I prefer to bind the binding stubs 16 of the assemblage of checks 5 between the back cover 7 and a heavy blank leaf 17 following the blank leaf 14, in two short plies 18 of strong binding paper or fabric, one of the plies being pasted detachably 70 on the heavy blank leaf 17, and the other on the inside of the back cover 7, so that when the checks 5 are all used up, the pasted plies 18 holding the check stubs 16 can be separated from the blank leaf 17 75 and the back cover 7 respectively and all the check stubs 16 held therein removed from between the covers 6 and 7. At the same time, the blank leaves 14 and 17 are 80 removed, and as the entry leaves alone remain between the covers 6, 7, a thin book of equal thickness throughout is formed which can be conveniently piled and stored.

To bring the front edges of the covers 6 and 7 approximately even when the checks 90 and stubs are thus removed, I make the front cover 6 so that its front edge will project beyond the front edge of the back cover when the book is full of checks, as shown in the drawings.

It is evident that many changes may be made in the details of my invention as here illustrated without departing from the boundaries of my invention as defined by the following claims.

By binding all the entry leaves together in the front of the book and all the checks together in the back of the book, reconciliation of deposits with checks and balance is greatly facilitated.

I claim as my invention:—

1. A check book having all its entry leaves assembled and bound together in one side of the back of the book adjacent one cover, and all its checks and their binding 110 stubs bound together in the other side of the back of the book adjacent the other

2
cover, a blank leaf between the entry leaves and the cover, and a fold of strong fabric in which the check stubs are bound, and the plies of which fold are secured detachably to the said blank leaf and cover respectively.

5. 2. A check book having all its entry leaves assembled and bound together in one end of the book and all its checks assembled and bound together detachably in the other

end of the book, the cover of said book adjacent the checks terminating normally inside the opposite cover, so that when the checks and stubs are detached, the back and front covers will terminate approximately together. 10

15. In testimony whereof I affix my signature.

SAMUEL J. HALPERIN.
